COMMUNICATION SYSTEM

Harry J. Nichols, Binghamton, and Henry L. Tholstrup, Endwell, N. Y., assignors, by direct and mesne assignments, to International Business Machines Corporation, New York, N. Y., a corporation of New York

Application December 12, 1935, Serial No. 54,134

17 Claims. (Cl. 178—53.1)

This invention relates to a communication system and more particularly to such a system as a printing telegraph or the like system.

It is the principal object of the invention to provide a novel communication system for the rapid, efficient, and accurate transmission of intelligence.

It is a further object to provide a selective signalling system in which the number of required selection intervals is greatly reduced, providing for increased speed and accuracy in transmission.

It is a further object to provide a signalling system of this character in which a selection of a desired element is effected through the utilization of signals having predetermined time relationship and also having other distinguishing characteristics.

It is a still further object to provide such a system in which the selectable elements are divided into a plurality of groups, each group having a predetermined time relationship with respect to the others, and in which further selection of the desired element in any group is effected in accordance with predetermined distinguishing characteristics of the signals.

Other objects and advantages will be apparent from the description, the accompanying drawings, and the appended claims.

In printing telegraph systems, the single impulse signal system, as contrasted with coded signal systems, depends in the matter of selection upon dividing a predetermined basic time period (usually the period of single revolution of a rotating member which imparts the time characteristic to the signals) into fractional time intervals in which the individual selections are performed. The timed signals representing the predetermined selections are thus differentiated from each other by the times at which they appear with reference to the beginning of the basic time period. The beginning of the basic time period may be marked by a start or synchronizing signal, or it may be unmarked, reliance being placed on the establishment and maintenance of a synchronous relation between the sending and receiving machines.

In the novel system herein disclosed, the beginning of the basic time period is preferably marked by a preliminary or start signal, and each fractional time interval may represent a plurality of desired selections, the particular selection depending on the character and timing of the start and/or printing signals.

The start signal and printing signals may be characterized by polarity, frequency and/or am-

plitude. It is found, however, that the simplest and most reliable characteristic, other than that of time, which can be imparted to a single signal impulse is that of polarity. Hence, in the following description, the added characteristic by which the group and sub-group selections are indicated will be referred to as polarity. It should be understood, however, that the signals may be given other selective characteristics if desired; for example, when carrier current transmission is used, the signals may be differentiated by time and frequency characteristics. Such a system is disclosed in copending application, Serial No. 7,674, filed February 23, 1935, and is adapted for use in conjunction with the present invention.

In the embodiment herein disclosed, the preliminary signal performs two functions, namely, to start a selecting device at the receiving machine, and to divide the selectable elements into two groups, each group comprising two sub-groups. The selecting or printing signal likewise performs two functions, namely, to select one sub-group of the group previously selected by the preliminary signal in accordance with the time relationship of the printing signal with respect to the preliminary signal, and to select the predetermined selectable element from the sub-group in accordance with the characteristics of the printing signal. For the sake of brevity, the preliminary signal will be referred to as the start signal, and the selecting signals as printing signals. This arrangement provides for reducing the number of required time intervals by arranging a number of selectable elements to be actuated at the same time interval, but in response to different characteristics of the signals. In the preferred practicing of the invention, start signals of two different characteristics are used, that is, a positive and negative polarity. Depending upon which start signal is sent, one or the other group of selectable elements is selected, the final selection of the predetermined element or group of elements being made by the printing signal in accordance with its time relationship with respect to the start signal. A still further selection, with further reduction of the number of time intervals, is obtained by imparting a distinguishing characteristic to the printing signal, and in the preferred embodiment to be herein-after described, printing signals of two different characteristics are utilized, that is, of positive and negative polarity. Each group of selectable members, one of which is selected in accordance with the characteristic start signal, is thus fur-

ther divided into two sub-groups, the final selection being made in accordance with the characteristics of the start signal, and the character and timing of the printing signal.

5 Thus a plurality of selectable numbers are arranged in the same time relationship (four in the embodiment of the invention herein described) and the desired selection is made in accordance with characteristic signals. This great-
10 ly reduces the number of time intervals required. The basic time period is thus divided into selection intervals equal in number to one fourth of the number of selections to be performed, plus one interval for the start signal. This reduction
15 in the number of time intervals required is of very great advantage, and provides for greatly increasing the speed of transmission, improving the accuracy of transmission, increasing the number of selections performed by the system, or
20 for obtaining a combination of several or all of these advantages in part.

In the drawings, Fig. 1 is a diagrammatic view illustrating the advantage of the system of the present invention as compared to a typical single impulse signalling system;

25 Fig. 2 is a view in schematic form showing an embodiment of the invention as applied to the transmitting end of a typical printing telegraph system;

30 Fig. 3 is a similar view showing a modified arrangement of transmitting apparatus;

Fig. 4 is a view showing an embodiment of apparatus as applied to the receiving end of the system; and

35 Fig. 5 is a view in schematic form showing an apparatus adapted for both sending and receiving functions.

In the several figures, excepting Fig. 1, like characters represent like parts.

40 Referring to Fig. 1 in detail, line A illustrates graphically the signals of a typical single impulse printing telegraph system adapted to perform 32 selections and employing one periodic synchronizing signal (or start signal) and 32 timed printing signals, all signals being of equal length and character. The time period of one printing cycle, representing one revolution of cycle of the sending distributor, is the basic time period and is represented by the letter T. The speed of transmission of intelligence over the system is inversely proportional to the period T. In such a system, assuming that N selections plus a synchronizing or starting function are to be performed, the signal impulses are sent during a fractional time unit equal to T divided by N+1. This fractional unit, which may be termed the selection interval since each selection is made during one of such units, is designated in the figure by t', and theoretically represents the duration of a signal impulse. In practice, some synchronizing margin is required, and the signals are somewhat shorter than the selection interval. In the figure, the signal impulse i' is shown as occupying two thirds of the selection interval t', the synchronizing margin m', one third of the selection interval.

45 Line B illustrates graphically the signals in accordance with the present invention. It is assumed that the distributor speed is the same as in the previous instance, hence the basic time period 50 is likewise represented by T. In this case, the printing signals are preceded by an equal start signal, and under the same assumptions as to the capacity of the system, the selection interval t is equal to T divided by the sum of N/4 plus one. 55 This follows from the system of signalling of the

invention which enables four selections to be accomplished during each selection interval except the first interval. The relative lengths of the signal i and synchronizing margin m are the same as in previous case. Fig. 1 represents comparative 6 conditions when the present invention is utilized to provide lengthening of the signal impulses without increasing the speed of transmission. In such case the accuracy is very much increased, by reason of the greater length of time that the 10 rotary contactor remains in contact with each of the segments. As above explained, however, the invention provides for obtaining combined advantages of increased speed of signalling, together with a partial lengthening of the signal 15 impulses and synchronizing margin to provide increased speed, accuracy, and reliability of transmission. Thus if the signal lengths are maintained the same as in a typical single impulse system, the speed of transmission with comparable 20 accuracy and reliability can be increased very materially, for example, in excess of three and one half times, with a system providing the number of selections indicated above. It also provides for obtaining a great increase in speed of transmission with comparable accuracy and reliability where such object is particularly desired.

25 Referring to Fig. 2 in detail, the apparatus shown performs the function of transmitting the start signal and timed printing signals to the line. 30 Local current pulses, which produce the line signals, are collected from their respective circuits by two similar distributors Q, Q'. Each rotary distributor includes a rotary contactor 20, 20' suitably driven, as for example by friction, by a 35 drive shaft (not shown) at a predetermined speed. The brushes of the rotary contactors are normally held in a predetermined rest position on a particular segment r, r' by pawls 24, 24' adapted to be actuated by release magnets 23, 23'. When released, rotary contactors 20, 20' sweep at uniform speed over the face of the stationary elements of the distributor comprising rings 21, 21', a double series of insulated segments, a, b, c, d, etc., and an elongated segment 22, 22'. The segments associated with the signaling function, designated by a, b, c, d, etc., are arranged in pairs, segments a and b of distributor Q being shown as located in the same time interval, the first following the rest segment r, so that they are simultaneously 45 contacted by rotary contactor 20; similarly segments c and d of distributor Q' are located in the first time interval following rest segment r' and are arranged to be simultaneously contacted by rotary contactor 20'. The segments associated 50 with each contactor are preferably mounted in three circles concentric with the ring and the axis of the rotary contactor. These parts are illustrated in linear development in order to simplify the diagram. The two distributors Q, Q' may be 55 positioned independently of each other, but preferably are placed concentrically in the same or in different planes to produce a more compact structure, a common drive means in such case serving to drive both contactors. The two distributors do not function simultaneously, but the signalling operations to be transmitted are divided 60 between them and only that distributor and its rotary contactor associated with the operated key is released and placed in rotation.

70 Four printer actuating or sending keys K_a, K_b, K_c, K_d are shown, each key representing one of a sub-group. The two sub-groups represented by keys K_a, K_b are associated with distributor Q, the two sub-groups represented by keys K_c, 75

Kd with distributor **Q'**. Key **Ka** represents the sub-group adapted to send a combination of start and printing signals of distinctive character, say a positive start signal and a positive printing signal, while key **Kb** represents the sub-group sending a positive start signal and a negative printing signal, the signals in each instance being sent via distributor **Q**. In like manner, key **Kc** represents the sub-group sending a negative start signal and a positive printing signal, while **Kd** represents the sub-group sending a negative start signal and a negative printing signal, the signals in each instance being sent via distributor **Q'**. The start signals sent by the group comprising the two sub-groups represented by keys **Ka**, **Kb** are positive; the start signals of the group comprising the two sub-groups represented by keys **Kc**, **Kd** are negative. The four keys named send printing signals during the same selection interval and hence the signals are not differentiated with respect to time. It will be understood that other similar groups and sub-groups of keys are arranged to send similar signals at other time intervals. For example the following table illustrates a suitable arrangement providing for the sending of distinctive signals for 32 operations, making use of 8 time intervals. In the table, the Roman numerals indicate the time intervals within which the second or printing signal is transmitted with reference to the first or starting signal.

	Start signal	Printing signal		Start signal	Printing signal
A	+	+I	Q	+	+V
B	+	-I	R	+	-V
C	-	+II	S	-	+V
D	-	-I	T	-	-V
E	+	+II	U	+	+VI
F	+	-II	V	+	-VI
G	-	+II	W	-	+VI
H	-	-II	X	-	-VI
I	+	+III	Y	+	+VII
J	+	-III	Z	+	-VII
K	+	+III	.	-	+VII
L	-	-III	.	-	-VII
M	+	+IV	f ₁	+	+VIII
N	+	-IV	f ₂	+	-VIII
O	-	+IV	f ₃	-	+VIII
P	-	-IV	f ₄	-	-VIII

The symbols *f₁*, *f₂*, etc., refer to the particular functions desired to be transmitted such as spacing, case shift, carriage return, line feed, and the like.

Each key **Ka**, etc., is associated with an individual key switch **Xa**, etc., directly or indirectly actuated, adapted to close an individual branch sending circuit. The key switches are connected to one of a pair of sending busses designated **Ps**, **Ns** respectively. These busses are connected to the terminals of a line connecting device, in this case a center tapped resistor **28** whose terminals are also connected to line terminals **26**, **27**. The center tap **29** is connected to the frame. Battery **B**, or other source of direct current, provides a current for signalling purposes. One side of battery **B** is connected to rings **21**, **21'**, the other side to the frame or ground which is thus established at negative potential.

The group of keys represented by **Ka** and **Kb**, including all the keys associated with distributor **Q**, actuate a universal ball **UB1** which in turn actuates auxiliary switch **X1**. Likewise, the group of keys represented by **Kc** and **Kd**, including all the keys associated with distributor **Q'**, actuate universal ball **UB2** which in turn actuates switch **X2**. Auxiliary switch **X1** closes the circuit from send bus **Ps** via capacitor **C1** to re-

lease magnet **23**. Capacitor **C1**, normally uncharged, functions in cooperation with auxiliary switch **X1** to restrict release magnet **23** to one operation for each operating cycle of switch **X1**, and thus prevents undesired repeat signals from being sent to the line in case the operator holds a key of the first group depressed overtime.

Auxiliary switch **X2** and capacitor **C2** perform the same functions with respect to keys of the second group.

Latch magnet **25**, the function of which is to latch down the depressed key and at the same time to lock all other keys against depression until the sending cycle is completed, is connected on one side to the elongated segments **22**, **22'** and on the other to the junction between capacitor **C3** and resistor **R3**. Capacitor **C3** is normally maintained in charged condition through resistor **R3**.

The operation when sending is as follows:—

Assuming first that key **Ka** is depressed, the contacts of key switch **Xa** are closed, and simultaneously, through the agency of universal ball **UB1**, the tongue member of auxiliary switch **X1** is moved to the lower contact. The latter action completes a circuit from positive battery to ring **21'**, via rotary contactor **20'** to segment **r**, thence through the winding of release magnet **23**, via contacts of switch **X1** and capacitor **C1** to send bus **Ps**, through resistor section **28a** and center tap connection **29** to frame and return to negative battery. A local current pulse through this circuit energizes release magnet **23**, causing pawl **24** to release rotary contactor **20** which is quickly set in motion by its drive means which operates continuously at substantially constant speed. It should be noted that center tapped resistor **28** is connected across line terminals **26**, **27**. The receiving end of the line terminates in some suitable item of receiving equipment such as a relay, transformer, etc., which completes the line circuit, hence part of the current pulse flows from terminal **26** through the line circuit, returning via terminal **27** and resistor section **28b** to center tap **29**. The local current pulse, and hence the line signal caused thereby, flows until capacitor **C1** is fully charged, but capacitor **C1** is made of such value that the current flow preferably is reduced to negligible value by the time contactor **20** leaves rest segment **r**. The signal transmitted as just described constitutes the start signal and its direction in the line is such as to represent positive polarity.

When rotary contactor **20** reaches elongated segment **22**, a second local circuit can be traced from ring **21** via contactor **20** to segment **22**, through the winding of latch magnet **25**, via capacitor **C3** to ring **21**. Capacitor **C3**, being already charged, discharges through the circuit just traced, energizing latch magnet **25** whose latch member **25a** hooks over the depressed key **Ka** and underneath all other keys, locking the keyboard in status quo, and preventing release of the operated key until the end of the transmitting cycle, and preventing operation of any other key during this time. Latch magnet **25** remains energized so long as contactor **20** is on segment **22**, holding current being supplied through resistor **R3**. The arrangement described provides a strong operating pulse to magnet **25** followed by reduced holding current, economizing on current and facilitating the prompt operation of the latch and subsequent release of the keyboard when contactor **20** leaves segment **22**.

When rotary contactor 20 reaches segment *a*, a third local circuit is established from ring 21 via contactor 20 to segment *a*, via contacts of switch Xa (held closed by the locking of the keyboard) to send bus Ps, and thence returning to negative battery by the path traced for the starting pulse. The current pulse through this circuit, continuing for the duration of the contact between contactor 20 and segment *a*, sends a corresponding positive signal to the line. This signal constitutes the printing signal for character A (for example), and is characterized by its polarity and by its timing relative to the start signal. Near the end of the revolution of contactor 20, the circuit of latch magnet 25 is broken as the contactor leaves segment 22, and latch member 25a is promptly withdrawn by the action of retractile spring 25s, unlocking the keyboard and permitting key Ka to rise under the action of its retractile spring (not shown). Universal bail UB1 rises with key Ka due to the reaction of the spring tongue of switch X1. As the upper contacts of switch X1 close, capacitor C1 is quickly discharged through resistor R1, restoring normal conditions in this circuit. At the end of the revolution, rotary contactor 20 is stopped on rest segment *r* by reason of being intercepted by pawl 24.

Assuming next that key Kb is depressed, the operations relating to the sending of the start signal, the release of rotary contactor 20, and the locking and unlocking of the keyboard are the same as described in connection with the operation of key Ka. Key switch Xb, operated upon the depression of key Kb, is connected to segment *b* and negative send bus Ns. Hence, when rotary contactor 20 reaches segment *b*, the local signalling pulse flows via send bus Ns and resistor section 28b to center tap 29; also in the line from terminal 27 through the line circuit to terminal 26, thence through resistor section 28a to center tap 29. Thus the current flow in the line circuit is in the opposite direction as compared with the previous case, and under the assumptions made, key Kb sends a printing signal of the same timing as that sent by key Ka, but of negative polarity.

Assume next that key Kc is depressed. In this instance, universal bail UB2 is actuated, closing the tongue member of auxiliary switch X2 to its lower contact, while at the same time the key closes the contacts of switch Xc. The local circuit first established is from positive battery to ring 21 via contactor 20 to segment *r*, through winding of release magnet 23', via contacts of switch X2 and capacitor C2 to negative send bus Ns, and resistor section 28b to center tap 29; also through the line circuit, resistor section 28a, center tap 29 and to ground, and to negative battery. The pulse through this circuit operates release magnet 23', charges capacitor C2, and sends a negative start signal to the line. Rotary contactor 20' is released by the operation of release magnet 23', and is set in motion by its drive means. Upon reaching segment *c*, a local circuit is established from ring 21', via contactor 20' to segment *c* and thence to positive send bus Ps. Hence a positive printing signal is sent to the line in the manner described in connection with the operation of key Ka, this signal occupying the same selection interval following the start signal as the printing signals sent by keys Ka and Kb. The operations of locking and unlocking the keyboard are as previously described, except that latch magnet 25 is energized via segment 22'.

Assuming next that key Kd is depressed, it will be seen that following the analysis of the sending of the start signal by key Kc and of the printing signal by key Kb, a negative start is sent via distributor Q, and a negative printing signal via segment *d* of distributor Q', all other operations being as described in connection with the previous cases.

The four examples given represent, as regards the signals sent to the line, two groups, the desired one of which is predetermined in accordance with the polarity or other distinguishing characteristic of the start signal, and four sub-groups of signalling elements, two sub-groups associated with each main group, the final selection being determined in accordance with the polarity or other distinguishing characteristic of the printing signal.

The signals in the above examples are sent in the fractional time division allotted to the start signal and first selection interval. Additional signalling elements in each of the four sub-groups, as for example, keys Ke, Kj, Kg, Kh, send similar characteristic signals, the printing signals being differentiated by time with relation to the start signal, that is, the selection interval with which they are associated. Hence the signals sent by each individual key become distinguished by reason of their combined time and other distinguishing characteristics.

It will be apparent to those skilled in the art that various suitable arrangements may, following the teaching of the present invention, be used to cause the reversal of the polarity of the line signals or to impart other variants in their character, and all such variations should be, and are intended to be, encompassed in the terms of the appended claims.

It is not necessary that the transmitting apparatus embody a plurality of rotary distributors and Fig. 3 shows an embodiment of a signal transmitter in accordance with the invention in which only one distributor is used, and in which four signalling keys are operatively associated with each transmitting segment. The four keys shown represent other similar groups of keys (one key for each selection to be performed over the system) making up a complete transmitting keyboard. Keys Ka, Kb, Kc, Kd are each provided with an individual key switch Xa, etc., but in this case four key switches are connected in common on one side to segment *i* of distributor Q; and on the other side, alternately to positive send bus Ps and negative send bus Ns.

Auxiliary switches X1 and X2 operatively associated with keys Ka, Kb, and Kc, Kd, respectively, connect in common to release magnet 23, but separately to send bus Ps and Ns respectively. The remainder of the arrangement is similar to that of Fig. 2, omitting distributor Q' and associated parts.

The operation is as follows:—

Upon the depression of any key, release magnet 23 is connected in a local circuit by either switch X1 or X2, hence rotary contactor 20 is released, and a start signal of proper polarity is sent to the line. For keys Ka and Kb and all other keys associated with switch X1, the start signal has positive polarity; for keys Kc and Kd and all other keys associated with switch X2 the start signal has negative polarity. When rotary contactor 20 reaches segment *i*, a circuit is completed via the key switch associated with the depressed key to the proper sending bus to transmit a signal of proper polarity. Thus actuation of keys Ka

and K_c causes the sending of positive printing signals, and keys K_b and K_d the sending of negative printing signals, in the first time interval following the start signal. Other groups of keys 5 function similarly in other time intervals. The operations of locking and unlocking the keyboard, etc., are as described in connection with Fig. 2. Without further detailed analysis, it will be clear that the operation of the system and the sending 10 of proper characteristic start and printing signals are the same as described above in connection with Fig. 2.

Referring now to Fig. 4 in detail, keys K_a , K_b , etc., of the receiving apparatus correspond to 15 those similarly designated at the sending apparatus in Fig. 2, but function at the receiving station to actuate the printer mechanism to print the selected character and to perform other functions relating to printing such as spacing, carriage 20 return, shifting, etc. Keys K_a , K_b , etc., are actuated by key magnets M_a , M_b , etc., which constitute the selectable elements of the receiver. Key magnets M_a , M_b , etc., are connected to segments a , b , etc., on one side and to receive busses 25 Pr , Nr according to group. It will be understood that the key magnets for the group of keys corresponding to those sending positive printing signals are connected to positive receive bus Pr and those for the group associated with negative printing 30 signals are connected to negative receive bus Nr . The two distributors Q , Q' , with associated release magnets 23 , $23'$ are similar to those of similar designation in Fig. 2, except that elongated segments 22 , $22'$ are omitted since they have 35 no relation to the receiving function. The distributors are arranged to be suitably driven by means similar to that at the transmitting apparatus, such as the friction drive means, providing for the driving of the distributor when released at 40 a speed corresponding to that of the distributor at the transmitter.

A suitable coupling device, such as transformer 30, connects the line to the receiving instrument, which in this instance comprises two electronic 45 relays T_1 and T_2 . Each electronic relay is preferably of the grid-controlled, gaseous discharge type and provided with a control grid, a plate or anode, and cathode, all contained in a sealed envelope containing gas or vapor following the 50 well known construction of these devices. The two electronic relays are arranged in push-pull fashion on the input side, the signals from the line being applied to the grids of relays T_1 , T_2 by input transformer 30 provided with primary $30p$ and 55 center-tapped secondary $30s$. The current for the anode circuits of T_1 and T_2 is supplied by battery B_1 , and the grids are given a normal non-operating bias by battery B_2 connected between the cathodes and the center tap of secondary $30s$. 60 The arrangement is such that line signals make one grid more positive, and the other more negative, in accordance with the polarity of the signals.

As is well known, the grid of a gaseous discharge tube can start the ionization of the tube but is 65 normally unable to stop the discharge through the tube when once started. A cut-off relay 32 , of retarded action type, is therefore provided to cut off the current in the anode-cathode circuits of 70 the electronic tubes after a predetermined time interval. The cut-off relay is timed to operate less quickly than the other magnets in circuit with it, and to hold the circuit open long enough to cause deionization of the tubes, thus permitting 75 the grids to regain control. It will be understood

by those skilled in the art that a polar relay with tongue set to neutral position can be used instead of the electronic relay arrangement shown which is equivalent in its action to that of a neutral polar relay. The electronic relay arrangement shown 5 has practical advantages, however, in that it operates only when a definite signal value obtains, is virtually instantaneous in action, and does not require the critical adjustments which characterize the polar relay.

The operation of the receiving equipment is as 10 follows:

Assume that a positive start signal followed by a positive printing signal has been sent from the sending machine by the depression of key K_a . 15 When the positive start signal is received from the line, transformer 30 makes the grid of one tube, say tube T_1 , more positive than normal, while the grid of the tube T_2 is made correspondingly more negative than usual. Assuming that 20 the signal is of proper amplitude, tube T_1 is ionized while tube T_2 is momentarily guarded against ionization. Tube T_1 becomes conducting upon ionization, and a local current pulse flows from positive B_1 , through the winding and contacts of 25 relay 32 to ring $21'$, via contactor $20'$ to segment r' , through the winding of release magnet 23 to positive receive bus Pr , thence to the plate of tube T_1 , via the ionized electron stream to cathode and 30 return to negative B_1 .

In response to this current pulse, release magnet 23 releases contactor 20 which is quickly set in motion by its drive means, and shortly thereafter, cut-off relay 32 opens its contacts, terminating the current pulse and causing tube T_1 to deionize, thus permitting its grid to regain control. Relay 32 immediately closes its contacts, restoring normal circuit conditions. As contactor 20 reaches segments a , b , the positive printing signal is received and tube T_1 again ionized. This 40 time the pulse circuit is established via segment a through the winding of magnet M_a to positive receive bus Pr and thence through tube T_1 to negative B_1 . The pulse through this circuit energizes magnet M_a , actuating its associated printer 45 key and causing the selected character to be printed. As in the previous instance, the pulse is terminated by the opening of the contacts of cut-off relay 32 and tube T_1 is deionized, restoring normal circuit conditions. Assuming next that key K_b at the transmitter has been depressed, the signals sent to the line comprise a positive start signal followed by a negative printing signal of the same timing as that sent by key K_a . In this case, tube T_1 is ionized by the start signal, and rotary 50 contactor 20 is released as before. As rotary contactor 20 reaches segments a , b , the negative printing signal is received and tube T_2 ionized, in effect connecting receive bus Nr to battery B_1 . Hence magnet M_b is energized, actuating its 55 associated printer key and causing the selected character to be printed.

As an example of the third case, assume that key K_c at the sender has been depressed, sending a negative start signal followed by a positive printing signal of the same timing as in the previous case. Tube T_2 is ionized by the start signal, in effect connecting receive bus Nr in circuit, and causes rotary contactor $20'$ to be released. As rotary contactor $20'$ reaches segments c , d , 70 the positive signal arrives to ionize tube T_1 . Receive bus Pr is thus connected in circuit, and magnet M_c energized causing the selected character to be printed.

As an example of the fourth case, it is assumed 75

that key **Kd** at the sender has been depressed, sending a negative start signal and negative printing signal to the line. Tube **T2** is thus ionized twice in succession, the first time causing rotary contactor **20** to be released, and the second time causing magnet **Md** to be energized, thus effecting the printing of the selected character.

Without further analysis, it will be clear that 10 by following the teaching of the invention other sub-groups of sending elements which send signals of the same timing can be utilized to control corresponding sub-groups of selectable elements in the same manner as the sub-group of 15 sending keys **Ka**, **Kb**, **Kc**, **Kd** and of control magnets **Ma**, **Mb**, **Mc**, **Md**.

Referring now to Fig. 5 in detail, the arrangements of Figs. 2 and 4 are therein shown combined into a send-receive arrangement capable 20 of alternately sending or receiving messages merely by operating a switch to make suitable changes in the circuit connections.

Keys **Ka**, **Kb**, **Kc**, **Kd**, which constitute the printer actuating keys, are each provided with an 25 individual key switch **Xa**, etc., and an individual actuating magnet **Ma**, etc. The key switches are of break-make type, the tongue and upper contact normally connecting the associated key magnet to the associated segment of the group distributor. The tongue and lower contacts, when 30 closed, connect the associated segment to the proper send bus. Suitable switching arrangements are shown to establish the proper circuits for sending and receiving conditions, the switch 35 elements being shown at convenient locations in the diagram, but in practice are ganged into a single switch having Send, Receive and Neutral positions. The remaining parts are the same as shown in Figs. 2 and 4.

40 Considering first the sending operation, it is to be understood that all switches have been closed to the position indicated by **S**. Upon the depression of key **Ka**, the tongue of key switch **Xa** is moved to the lower contact and universal 45 bail **UB1** closes the tongue of auxiliary switch **X1** to the lower contact. Rotary contactor **20** is thereupon released, latch magnet **25** operated, and positive start and printing signals transmitted as described in connection with Fig. 2. The sending 50 operations upon the depression of keys **Kb**, **Kc**, **Kd** are likewise as described in connection with Fig. 2. Additional sub-groups of keys, following the pattern of the sub-group including key **Ka**, etc., can be added to the system to the 55 extent desired, in other time interval positions.

Considering next the receiving operations, for receiving the gang switches are moved to position **R** disconnecting auxiliary switches **X1**, **X2**, latch magnet **25**, and resistor **28** together with the sending busses, and connecting transformer **30** to the line. The receiving operations as described in connection with Fig. 4 then become applicable to Fig. 5.

It will thus be apparent that the embodiment 65 of the invention just described provides an efficient send-receive arrangement in which the larger part of the apparatus functions both in sending and receiving, with consequent advantages in respect to simplicity and low costs.

70 The invention herein described enables any number of selections to be accomplished over a single circuit by a combination of two signals of equal magnitude, the first signal being invariable with respect to time, but determinately 75 variable in character, while the second signal is

determinately variable with respect to time and character. Other combinations of characteristic start and printing signals may be made as desired to provide the same, less, or even a greater number of selection steps in any one time interval, 5 the invention thus providing a system of signalling which provides for obtaining great speed, accuracy and reliability.

While the methods described herein, and the forms of apparatus for carrying these methods 10 into effect, constitute preferred embodiments of the invention, it is to be understood that the invention is not limited to these precise methods and forms of apparatus, and that changes may be made in either without departing from the 15 scope of the invention which is defined in the appended claims.

What is claimed is:

1. In a communication system of the character described the method of signalling which comprises the steps of sending a preliminary signal of distinctive character indicative of a selecting starting operation to be performed, and thereafter sending a second signal having predetermined time relation to said preliminary signal, 25 said signals being indicative of a desired operation to be performed; receiving said signals, utilizing said first mentioned signal to select from a plurality of rotary elements the one element predetermined in accordance with the characteristics 30 of said preliminary signal, releasing said selected rotary element from a predetermined phase position, and utilizing said second mentioned signal in cooperation with said selected rotary element to perform the operation as desired. 35

2. In a communication system of the character described, the method of signalling which comprises the steps of sending a start signal of distinctive character indicative of a selective start- 40 operation to be performed, and thereafter sending another signal in predetermined time relationship with said start signal, said signals being indicative of a specific operation to be performed; receiving said signals, effecting a predetermined group selection as determined by the characteristics of said start signal, and effecting a further selection from the selected group and performing the operation desired as determined by the time relationship of said second signal 50 with said start signal. 45

3. In a communication system of the character described the method of signalling which comprises the steps of sending a start signal of distinctive character, sending a second predetermined timed signal having predetermined characteristics with respect to said start signal, said signals being indicative of a desired operation to be performed; receiving said signals, effecting a predetermined group selection as determined 60 by the characteristics of said start signal, and effecting a further selection from the selected group and performing the desired operation in accordance with the characteristics of said second signal and the time relationship thereof with respect to the start signal. 65

4. In a communication system of the character described the method of signalling which includes the steps of sending a start signal of predetermined polarity characteristics indicative of 70 a selective starting operation to be performed, and thereafter sending a second signal having predetermined characteristics with respect to said start signal, said signals being indicative of a desired operation to be performed; receiving 75

5 said signals, effecting a predetermined group selection as determined by the polarity characteristics of said start signal, and effecting a further selection from the selected group and performing the desired operation in accordance with the characteristics of said second signal.

5. In a communication system of the character described the method of signalling which includes the steps of sending a start signal of distinctive character, sending a second signal in predetermined time relationship with said start signal and of predetermined distinctive character, said signals being indicative of a desired operation to be performed; receiving said signals, effecting a predetermined group selection as determined by the characteristics of said start signal, and effecting the further selection from the selected group and performing the desired operation in accordance with the time relationship between the start signal and said second signal, and in accordance with the distinctive characteristics of said second signal.

6. In a communication system of the character described, the method of signalling which includes the steps of sending a start signal of distinctive character, sending a second signal in predetermined time relationship with said start signal and of predetermined polarity characteristics, said signals being indicative of a desired operation to be performed; receiving said signals, effecting a predetermined group selection as determined by the characteristics of said start signal, effecting the further selection from the selected group and performing the desired operation in accordance with the time relationship between said start signal and said second signal, and in accordance with the polarity characteristics of said second signal.

7. In a communication system of the character described, the method of signalling which includes the steps of sending a start signal of distinctive polarity characteristics indicative of a selective starting operation to be performed, and thereafter sending another signal in predetermined time relationship with said start signal and of predetermined polarity characteristics, said signals being indicative of a desired operation to be performed; receiving said signals, effecting a predetermined group selection as determined by the polarity characteristics of said start signal, and effecting a further selection from the selected group and performing the desired operation in accordance with the time relationship between said start signal and said second signal, and in accordance with the polarity characteristics of said second signal.

8. In a communication system of the character described, the combination of a keyboard, means operative upon the actuation of each of said keys for generating a start signal of distinctive characteristics, and including means for generating a second signal having predetermined timed characteristics with respect to said start signal, said signals being distinctive for each of the operating keys, means for transmitting said signals, means for receiving said signals, a receiving keyboard having operating elements corresponding to those at the transmitter, and means for effecting the operation at the receiver of the element corresponding to that operated at the transmitter including means for selecting a predetermined group of said elements in accordance with the characteristics of said start signal, and means for selecting the desired operating element from said group in accordance with the time characteristics

of said second signal in relation to said start signal.

9. In a communicating system of the character described, the combination of a keyboard, means operative upon the actuation of each of said keys for generating a start signal of distinctive characteristics, and for generating a second signal having predetermined characteristics with respect to said start signal, said signals being distinctive for each of the operating keys, means for transmitting said signals, means for receiving said signals, a receiving keyboard having operating elements corresponding to those at the transmitter, and group selecting means for selecting the operating element at the receiving station corresponding to that at the transmitting station comprising a plurality or rotary elements, means for selecting and releasing for operation a predetermined rotary element including means controlled in accordance with the characteristics of said start signal, and additional means associated with the selected rotary element and controlled in accordance with the relationship between said second signal and said first signal for effecting the final selection of the desired element.

10. In a printing telegraph system of the character described, means for generating polarized start signals and timed and polarized printing signals, transmission means, means for receiving said signals, individual selectable printer actuating means, group selecting means actuated by said start signals for selecting a predetermined group of said printer actuating means including means controlled in accordance with the polarity of said start signals, and means controlled in accordance with the timing and polarity of said printing signals for selecting the desired one of said printer actuating means.

11. In a printing telegraph system of the character described, the method of signalling which comprises the steps of sending signals indicative with respect to time of the beginning of a predetermined time interval and with respect to character of a selective operation to be performed, and thereafter sending signals differentiated as to time within said time interval and differentiated as to character, and then in accordance with said signal combinations effecting predetermined selective operations.

12. In a printing telegraph system, means for transmitting signal impulses indicative with respect to time of the beginning of a cyclic interval and with respect to character of a selective operation to be performed, and means for thereafter transmitting signal impulses differentiated with respect to time and character indicative of predetermined operations to be performed.

13. In a printing telegraph system of the character described, a plurality of actuatable elements, means for transmitting a characteristic signal combination upon the actuation of any of said elements comprising means for transmitting a single impulse indicative with respect to time of the beginning of a predetermined cyclic interval, and with respect to characteristics of a group selective operation to be performed, and means for thereafter sending a single impulse having predetermined timed relation with respect to said first mentioned impulse.

14. In a printing telegraph system, in combination, means for transmitting in cyclic order a characteristic starting impulse followed by a printing impulse having predetermined characteristics in relation to said starting impulse,

means for receiving said impulses, a plurality of rotary distributors, a plurality of selectively operable elements, means controlled in accordance with the characteristics of said starting impulse for placing a predetermined one of said rotary distributors in operation, and means co-operating with said selected rotary distributor and operable in accordance with the characteristics of said printing impulse in relation to said starting impulse for selecting and effecting operation of the desired one of said operable elements.

15. In a communication system of the character described, the combination of a plurality of operative elements adapted to be selectively operated, means for sending signals indicative of the particular operated element comprising means for sending a start signal, and thereafter a second signal, including means for imparting to said start signal distinctive characteristics which are indicative of a group of elements including said operated element, and means to impart to said second signal a predetermined time relationship with said start signal indicative of said operated element within the selected group.

16. In a communication system of the character described, the combination of a plurality of operative elements adapted to be selectively operated, means for sending a distinctive signal combination upon the operation of any of said elements including a preliminary signal having predetermined distinctive characteristics, and a second signal having predetermined time relationship with said preliminary signal, a receiving station, means for receiving said signals, a plurality of operative elements at said receiving station, and means for operating the element

at said receiving station corresponding to said operated element at the sending station including a plurality of rotary elements, means controlled in accordance with the characteristics of said preliminary signal including means for selecting a desired one of said rotary elements and placing said selected element in operation, and means cooperating with said selected rotary element for selecting the predetermined operating element including means controlled in accordance with the time relation between said second signal and said preliminary signal.

17. A communication system of the character described comprising a plurality of operative elements adapted to be selectively actuated, a rotary member, means for retaining said member in a predetermined position of rest, means effective upon the actuation of one of said operative elements for releasing said retaining means and placing said rotary member in movement, means acting upon the actuation of any of said operative elements for sending a signal combination of distinctive characteristics for each such element, including means associated with the actuated element for sending a preliminary signal of distinctive characteristics indicative of a preliminary selective operation and for releasing said retaining means to place said rotary member in movement, and means also associated with said actuated element and with said rotary element for sending a subsequent signal of distinctive characteristics in predetermined time relation with said preliminary signal.
